CLAIM

The ornamental design for a truck body mounted refrigeration unit, substantially as shown and described.

DESCRIPTION

FIG. 1 is a front elevational view of a truck body mounted refrigeration unit showing our new design;

FIG. 2 is a top plan view thereof;

FIG. 3 is a side elevational view thereof, the opposite side being identical thereto.

The rear and bottom of the refrigeration unit are substantially flat and unornamented.

FIG. 2**FIG. 1****FIG. 3**
